Filed April 9, 1947

UNITED STATES PATENT OFFICE

2,608,193

PROJECTION SLIDE FILE

Archie J. McMaster, Deerfield, Ill., assignor to
G-M Laboratories, Inc., Chicago, Ill., a corpora-
tion of Illinois

Application April 9, 1947, Serial No. 740,349

3 Claims. (Cl. 129—15)

1.

My invention relates to a projection slide file which simplifies indexing, storage and handling of the slides during projection.

A considerable industry has developed in the production and projection of miniature transparencies, usually colored photographs, in which the negative is developed to form a positive image when projected. Such miniature transparencies are employed extensively by amateurs but are also employed semi-professionally as, for example, by lecturers addressing technical societies, in class room work and the like. The miniature transparencies of the type described are conveniently mounted to form 2 x 2 slides, either by encircling the film directly with a paper frame to form a so-called ready mount, or by placing the film between a pair of glass plates which are held together by a paper or like binding to produce a usual type of glass slide. Slides of the type described are indexed in various ways, but usually by placing a number or other identifying symbol on the slide and cross matching it to an index which describes the slide. So far as I know, no fully satisfactory means for storing, indexing and handling slides during projection has been made available for the amateur or semi-professional using miniature transparencies of the type described.

The principal object of my invention is the provision of an improved slide file.

Another object is the provision of a slide file so constructed and arranged that the slides are readily associated with the card index without the need of cross reference.

Still another object is the provision of a slide file in which the slides can be withdrawn and into which they can be inserted directly during projection, the same file being used to store, classify and index the slides.

I have embodied features of my present invention in a slide file, a preferred embodiment of which is shown in the drawings in which—

Fig. 1 is a perspective view showing the slide file in the position for projecting, but with a center portion of the slides removed to illustrate structural details;

Fig. 2 is a transverse sectional view taken on the line 2—2 of Fig. 1;

Fig. 3 is a fragmentary longitudinal vertical sectional view taken on the line 3—3 of Fig. 2;

Fig. 4 is a fragmentary sectional view taken on the line 4—4 of Fig. 1;

Fig. 5 is a fragmentary sectional view partly in elevation taken on the line 5—5 of Fig. 2 looking in the direction of the arrows;

Fig. 6 is a reduced perspective view showing the slide file with the cover in position and with the file and contents ready for storage;

Fig. 7 is a transverse sectional view taken on the line 7—7 of Fig. 6, looking in the direction of the arrows; and

Fig. 8 is a slightly enlarged perspective view showing a spring hinge member employed to support an index card in adjustable position on the edge of the slide file body.

The slide file of my invention comprises a file body 10 and cover 11 which may function to support the body 10 in the manner shown in Fig. 1 or to form a closure therefor as shown in Figs. 6 and 7. The body 10 is provided with vertical separators 12 forming aligned vertical ways for receiving slides 13. An index card 14 is provided with lines 16 and is adapted either to be supported in a horizontal plane as shown in Fig. 1, or to lie flat against the side of the file body as shown in Fig. 7. The index card 14 is formed of relatively heavy and durable fiber and has a plurality of reinforcing eyelets 17 into which an upper angular portion of a spring hinge member 18 is secured. The spring hinge member is of generally U-shape as shown in Fig. 8 and extends through a small opening 19 in the lower portion of the body 10 and a top part lying in a recess at the top edge of the file body as shown particularly in Fig. 2. The other leg of the generally U-shaped spring hinge member lies along the outside surface of the file body and is drawn in with such tension that the index card 14 may be held in the position shown in Fig. 2, or can be rotated as on a hinge to the position shown in Fig. 7. It will be noted that there is a top projecting ledge 21 so positioned that when the cover 11 is applied the card index 14 may readily lie between the body and cover without binding or marring.

The inside end surfaces of the cover 11 are provided with generally T-shaped stop members 22 so constructed and arranged that when the slide body is placed in the inverted cover in the manner shown in Figs. 1—3, inclusive, the file body is supported well above the cover in a position making the slides easily accessible. The upper end edges of the file body are provided with recesses 23, however, so arranged that the squat leg of the T, comprising, in a sense, a projection from the cross portion of the T, extends into the associated recess 23 as appears clear from Fig. 7 and permits the cover to descend sufficiently to substantially entirely enclose the slide body and slides contained therein. The

construction and arrangement of the stop member 22 and edge recesses 23 are, therefore, such that when the slides are being projected and the slide body is supported within the cover the slides set well up so that they are reached readily. When the cover is reversed, on the other hand, a storable package is produced in which the contents of the package are fully protected.

Heretofore, I referred to the lines 16 without comment, but it will be fairly obvious that these lines are intended and may be used for listing slides by description or by the use of any identifying symbol. I find that without any attempt at such accuracy of production as would lead to excess manufacturing cost, the space between the lines 16 may be made to correspond substantially exactly with the spaces between the separators 12, so that a slide will always be stored exactly along side the name and/or number or other symbol identifying that particular slide. The individual slides can be identified by name, the slides can be grouped, they can be identified by number or other symbol but however identification is accomplished there is a great advantage in having the identifying symbol immediately adjacent the slide or group of slides which are identified. Generally, three so-called ready mounts can be mounted in the space usually occupied by one glass slide, and, accordingly, in a slide file built to accommodate a given number of glass slides, approximately three times the number of ready mounts can be stored therein.

In addition to identifying the slides by reference to the index card 14, I provide an indexing or cataloging space 24 on the end of the cover 11 so that when stored, the contents of the package can be readily identified.

I have found the features of my invention to be of unusual advantage in the production of a slide file substantially identical with that shown in the drawings. This desirably acceptable embodiment has a capacity of thirty-two glass slides and ninety-six ready mounts or an assortment of both. The slides adapted to be accommodated are the usual 2 x 2 slides, and the total package of cover and file body is only 2 $\frac{3}{8}$ " x 1 $\frac{5}{8}$ " x about 7 $\frac{1}{2}$ ". As slides are obtained, they may be accumulated directly in the slide file, and appropriate notations made not only on the index card but on the cataloging space 24 on the end of the cover. The slides are easily located for projection, and after projection are returned to their proper space without any danger of confusion, delay or inconvenience, even when operating in the dim light necessary for good projection. When the projection procedure has been completed, the slides are back in position, and the only requirement is to remove the cover from the position shown in Fig. 1, lower the index card 14 and replace the cover as a closure in the manner shown in Fig. 6.

What I claim as new and desire to protect by Letters Patent of the United States is:

1. A slide file of the character described, comprising a file body having slide ways for projection slides supported in the file body, said file body having end top recesses, and a projecting ledge along one top side edge thereof, hinge spring members of generally U shape having legs of the U at opposite surfaces of the said side and with a top angular portion lying just below said top side projection, and forming a hinge loop, an index card member having apertures along one side through which said angular portions extend, said index card provided with lines so positioned that matter written thereon will lie opposite the slides, the card adapted to be held horizontally by the hinge spring members or along the side of the file body below said side projection, and a cover having stop members on its inside end surfaces to support the file body when the cover is reversed, said stop members extending into the said top end recesses, whereby to permit the cover to function as a complete closure member.

2. A slide file of the character described, comprising a file body of generally rectangular shape provided with slide ways for supporting the slides in spaced relation, a slide index card hinged to an upper side edge of the file body, and means for supporting said index card in a horizontal position at a level with said upper side edge or vertically along the said side below the said upper edge, said last mentioned means including spring hinge members having top angular portions extending through openings in the index card along one edge thereof.

3. A slide file of the character described, comprising a file body having slide ways for projection slides supported in the file body, said file body having a projecting ledge along one top side edge thereof, hinge spring members of a generally U shape having legs of the U at opposite sides of the said side, and with a top angular portion lying just below said top side projection and forming a hinge loop, and an index card member having apertures along one side through which said angular portions extend, said index card provided with lines so positioned that matter written thereon will lie opposite the slides, the card adapted to be held horizontally by the hinge spring members or along the side of the file body below said side projection.
